LIP STICK HOLDER

Blake Allen Seaver, Springfield, Mass., assignor
to Blake Manufacturing Corporation, Springfield, Mass., a corporation of Massachusetts

Application May 19, 1934, Serial No. 726,432

4 Claims. (Cl. 206—56)

This invention relates to improvements in lip stick holders of which the following is a full, clear, and exact description.

An object of my invention is to provide a holder for projecting the stick beyond the upper edge of the holder when it is to be used, and to draw it into the holder, when not in use.

A further object is to provide means for imparting a slow, axial movement to the lip stick, resulting in a particularly smooth, easy, action, with a minimum of frictional resistance to operation.

Broadly, my invention comprises an outer and inner tubular member, each formed with a spiral slot which terminates near the upper and lower edges, or ends, of the two tubular members. A carrier member is provided in which the lip stick is placed. This carrier is provided with a pin member, one end of which is located in the spiral slots of the two tubular members. Attached to the inside tubular member is a base, or cap member, for rotating the same, which causes the pin in the carrier to follow the spiral slot, and, at the same time, to follow the spiral slot in the outer tubular member, whereby the combined action of the two spiral slots will cause the carrier to travel in an outward, or inward direction, depending upon the direction of rotation of the base or cap. The spiral slots in the two tubular members are arranged in opposite directions, that is to say, one is a right hand slot and the other a left hand slot.

The outer, tubular member has tightly fitted thereon an outer sleeve member formed with an annular bead, this bead providing a seat for a suitable cap member for closing the open end of the holder, when the lip stick is not in use. A collar, secured on the inner tubular member, is provided with means for frictionally engaging the outer sleeve member, for holding the lip stick in any desired projected position.

Referring to the drawing:—

Fig. 1 is a vertical, sectional view through the axis of the holder, showing the two slotted tubular members, the pin therein, and the carrier for the lip stick.

Fig. 2 is a detail view of the closure cap.

Fig. 3 is an elevational view of the outside sleeve.

Fig. 4 is a detail view of the collar for the inner tubular member.

Fig. 5 is a detail view of the base for operating the inner, slotted, tubular member.

Fig. 6 shows the outer, spiral, guide slotted sleeve, or tubular member.

Fig. 7 shows the inner, spiral, slotted tubular guide member.

Fig. 8 is a detail view of the stick holder, or carrier.

Figs. 9 and 10 are detail views of the blanks, after being formed with an inclined slot in each blank and before they are rolled to form a tubular member for assembling the same.

Fig. 11 is a partial, sectional view, similar to Fig. 1, illustrating a modified construction for securing the inner, special, slotted tubular member to the operating base member, and

Fig. 12 is a cross, sectional view on the line 12—12 of Fig. 1, illustrating the collar and arcuate spring fingers, frictionally engaging the outside sleeve.

Referring to the drawing in detail:—

1 indicates the closure gap; 2 the outside sleeve. It is formed with the bead 2'. 3 indicates a base member, having a knurled edge 3'. This member is formed with a struck or bent-in part 4, which enters a slot 5 in the inside tubular guide member 6 for rotating this tubular member, when the base is turned. Located outside of the member 6 is the tubular member 7 having the spiral slot 8, which terminates near the opposite ends, as shown. The inside, tubular member 6 is formed with a spiral slot 9, which is a right hand one, while the slot 8 in the member 7 is a left hand one. These two tubular slotted members are assembled one within the other, as shown in Fig. 1. 10 indicates the carrier member, in which the stick 11 is placed. 12 is a pin which is located in the carrier 10. This pin, as shown, has one end located in the spiral slots 8 and 9; its other end is supported in an elongated opening 13 formed in the struck-up tubular part 13 and is formed with a conical centering end 13'.

When the base piece 3 is rotated right handed, the inner tubular guide sleeve 6 is rotated through 40 the connection of the struck-up part 4 and slot 5. The outer tubular member 7 is held stationary by frictional engagement with the outside sleeve 2. Thus, when the member 6 is revolved while the member 7 remains stationary, the pin 12 is caused 45 to advance in an upward direction in the slots 8 and 9. The combined action of these two spiral slots on the movement of the pin 12 and the stick carrier is to retard the vertical movement of the carrier and the stick 11 therein, relative to the 50 rotary movement of the member 6, and, to minimize the frictional resistance of the pin 12 on the member 7. In constructions now known and used in the art, using in combination a movable sleeve with a spiral slot and a stationary sleeve 55

with a vertical slot, or vice versa, it will be obvious that vertical movement of the pin and carrier will be in direct ratio to rotary movement of the base, whereas, in my construction, involving the use of opposed spiral slots, the vertical movement of the pin and carrier is approximately half the movement of the base. In other words, when a spiral and a vertical slot co-operate to move the carrier, the carrier makes one revolution for each revolution of the base, but, when opposed, spiral slots co-operate to move the carrier, the carrier makes only one-half revolution for each revolution of the base. The result of this ratio is to move my carrier in a vertical direction at approximately half the speed, relative to rotary movement of the base member, of the carrier motivated by a pin engaged in co-operating spiral and vertical slots.

14 indicates a collar member that is secured to the slotted, inside guide, tubular member 6 for retaining it in place. The two tubular slotted guide members 6 and 7 are rolled from flat stock, as indicated in Figs. 9 and 10, and the inner member 6 is confined at the bottom by the base member 3 and at the top by the collar 14. The outer member 7 is confined within the sleeve member 2, between the base member 3 and the collar 14.

Frictional engagement between the inner tubular member 6 and the sleeve member 2 is provided by arcuate or radial spring fingers 16, formed on the collar 14 and having their axes parallel to the axis of the tubular members 6 and 7. These arcuate spring fingers 16 project slightly beyond the outer surface of the collar 14, and engage at their crowns the inner surface of the sleeve member 2, which is tightly fitted on the outer, tubular member 7.

These fingers are relatively longer than their widths, and their free ends located away from the inner surface of the cylinder 2.

In the modified construction, shown in Fig. 11, the inner, tubular member 6 is secured in the base member 3 by enlarging the end 6' within the limited portion 3' of the base 3, thus forming a bell-shaped end which firmly grips the base 3.

I am well aware that it is not new to employ outer and inner slotted, tubular members; one having a spiral slot and one having a straight slot, but I believe the use, or employment of two tubular members, each having a spiral slot, and one slot opposed in pitch to the other, for controlling the movements of the carrier is new. By reason of the two tubular slotted guide members

8 and 7 having their pitches opposed to each other, the annular motion of the base 3 is substantially greater than the annular movement of the carrier 10, whereby the carrier and its stick is moved outward in a comparatively slow movement. This retarded movement results in a relatively easier and smoother action, resulting in a greatly improved "feel" in the operation of the holder.

What I claim is:—

1. In a lip stick holder, two tubular members, one located within the other and each having a spiral slot therein, the pitches of which are opposed, a carrier member, a pin therein, the pin being located in the said slots, base means for rotating one of the members comprising a base piece having a bent-in part which enters an opening in one of the said members which is to be rotated, a collar on the upper end of the inner tubular member, the base means having a part on which the outer tubular member rests and said collar serving to confine the outer tubular member.

2. In a lip stick holder, a carrier and support for the lip stick comprising, in combination, a shell formed with an opening in its side and an inwardly projecting boss opposite said opening, said boss being provided with an elongated opening therein, and a pin in said shell and bearing in said openings with an end thereof projecting beyond the outer surface of said shell.

3. In a lip stick holder, a carrier and support for the lip stick comprising, in combination, a cup-shaped member provided with an opening in its side wall and formed with an inwardly projecting boss opposite said opening, said boss being provided with an opening diametrically opposite the opening in the side wall of the cup-shaped member, and a pin having a square end and a conical end, said pin being disposed within said cup-shaped member and bearing in said openings with the square end thereof projecting beyond the outer surface of said cup-shaped member opposite said boss.

4. In a lip stick holder, having inner and outer tubular members revolvable relative to each other, and an outer sleeve secured on the outer tubular member, a collar secured on the inner tubular member and formed with radial spring fingers relatively longer than their widths for frictionally engaging the inner surface of the outer sleeve, the free ends of said fingers being bent clear of said inner surface.

BLAKE ALLEN SEAVER.
